(57) **CLAIM**

The ornamental design for a powder actuated tool, as shown and described.

DESCRIPTION

FIG. 1 is a left, front perspective view of a powder actuated tool according to the design, the right, front perspective view being mirror symmetrical;

FIG. 2 is a left, rear perspective view thereof, the right, rear perspective view being mirror symmetrical;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a front view thereof.

The broken lines shown in the drawings illustrate portions of the powder actuated tool that form no part of the claimed design.

1 Claim, 6 Drawing Sheets
